UNITED STATES PATENT OFFICE.

RAYMOND N. EHRHART, OF PITTSBURG, PENNSYLVANIA, ASSIGNOR TO THE WESTINGHOUSE MACHINE COMPANY, A CORPORATION OF PENNSYLVANIA.

ELASTIC-FLUID TURBINE.

968,839.

Specification of Letters Patent. Patented Aug. 30, 1910.

Application filed March 9, 1905. Serial No. 249,276.

To all whom it may concern:

Be it known that I, RAYMOND N. EHRHART, a citizen of the United States, and a resident of Pittsburgh, in the county of Allegheny and State of Pennsylvania, have invented a new and useful Improvement in Elastic-Fluid Turbines, of which the following is a specification.

This invention relates to elastic fluid turbines, and, as an object, has the production of means for counterbalancing the end or longitudinal thrust to which the rotating shafts or rotors thereof are subjected.

A further object has been the production of means for automatically balancing the end thrust of turbine rotors, due to any cause, whether from the unbalanced fluid pressure, as in a single flow turbine, or a propeller thrust and the fluid pressure as encountered in marine turbines, or the weight of the rotor and fluid pressure as encountered in vertical turbines.

To obtain these and other objects, I have introduced in connection with elastic fluid turbines, what may be called a balancing-chamber.

In the drawings accompanying this application and forming a part thereof, Figure 1 is a longitudinal section of an elastic fluid turbine fitted with such a balancing-chamber: Fig. 2 is a longitudinal section of an elastic fluid turbine with a modification in arrangement and location of the said balancing-chamber.

Referring to Fig. 1, the motive fluid enters the exterior casing 3 of the turbine through the port 4. From the annular chamber 5, connected with the port 4, it passes through the high pressure blading on the drum 6 to the annular chamber 7, from the chamber 7 the fluid passes through the intermediate pressure blading on the drum 8 into the annular chamber 9, and from the chamber 9, through the low pressure blading on the drum 10, it is discharged into the exhaust end of the turbine, from which it is exhausted into a condenser, or the atmosphere, through an exhaust port 11. A secondary port 12 in connection with the chamber 7 is arranged to admit fluid at initial pressure to the intermediate pressure drum 8. This secondary inlet is controlled by a

governor and is operated in case of overloading the turbine. Serrated collars 13 and 14, mounted on the shaft 2 at either side of the chamber 15, interleaving with oppositely formed collars mounted on the exterior casing 3 of the turbine, present a circuitous path to the working fluid, and the tendency of the fluid to leak past these collars is materially decreased.

In the type of turbine just described, the entire surface of the rotor is subjected to fluid pressure of more or less intensity, and as one surface only of the drum is exposed to the fluid pressure, the rotary spindle will tend to move in the direction of this pressure, that is, toward the exhaust end of the turbine. The pressure of the elastic fluid acting on drum 5 is balanced by an equal and opposite pressure on the collar 13, but, as is readily seen from the drawing, no such balancing action is obtained in the case of the drums 8 and 10. Therefore, as a means of counterbalancing this resultant pressure and any exterior pressures to which the rotor may be subjected, I have introduced within the interior casing of the elastic fluid turbine a chamber 16 with a source of supply 17, through which the motive fluid at initial pressure is introduced, the size and location of the passage 17 permits only a restricted flow of the motive fluid, the reason for this is more fully described hereinafter.

Mounted on the shaft 2 and at either side of the chamber 16, are serrated collars 18 and 19 interleaving with oppositely formed collars 20 and 21 mounted on the exterior casing of the turbine. The interleaving serrations of these collars have been shown large for the purpose of description only as in reality they are of the same form and shape as those with which the collars 13 and 14 are supplied. The interleaving collars 18 and 20 and 19 and 21 are so arranged that any longitudinal motion of the shaft decreases the clearance between the adjacent faces of the grooves and ridges to such an extent that they become practically fluid tight, while in their normal position they are arranged to present a moderately restricted passage for the fluid.

The chamber 16 is so designed that the effective pressure along the spindle due to

the initial fluid pressure in said chamber, will be in opposition to a longitudinal exterior thrust, or to the pressure of the working fluid on the drums 8 and 10. In the 5 turbine illustrated the lateral and exposed surface of the collar 18 exceeds that of the collar 19, and the effective pressure in the chamber 16 will be exerted in the direction of the steam end of the turbine and will 10 tend to shift the spindle in that direction. When the longitudinal pressure of the working fluid on the drums 8 and 9, or longitudinal thrust from some exterior cause is sufficient to move the spindle laterally, the serrations of the collars 18 and 19 interleaving 15 with the like serrations on the oppositely formed collars 20 and 21 become effective, by their reduced clearance, in sealing the chamber 16. If initial pressure is now admitted 20 at 17, the spindle will be forced toward the admission end of the turbine, but the clearance between the interleaving serrations will, at the same time, be increasing, and the confined fluid in the chamber 16 25 will leak past the sealing collars. As the flow through 17 is restricted, a degree of leakage will be obtained at some position of the spindle such that the motive fluid in 12 can exert only sufficient pressure to overcome 30 the longitudinal thrust on the spindle. In this way the pressure in the chamber 16 will adjust itself to balance and overcome any end thrust to which the rotor is subjected without materially increasing the 35 resistance to rotation.

By the arrangement and location of the 40 passages for motive fluid, I have obtained means for utilizing the necessary leakage of the fluid from the chamber 16 as a working agent on the rotor. The fluid leakage through the collars 18 and 20 from the high 45 pressure chamber 16 into the intermediate pressure chamber 9 combines with the steam in the said passage and is utilized in working on the drum 10. The fluid leaking between the collars 19 and 21 also combines with the fluid exhausted from the intermediate drum 8 in working on the low pressure drum 10. By a further arrangement of 50 pipes and passages it is possible to utilize the steam leaking from any working chamber of the turbine in a working chamber of lower pressure. The leakage from the high pressure chamber 5 past the collars 13 into the chamber 15 is carried by the pipe 22 into 55 the chamber 7 where it combines with the fluid exhausted from the high pressure drum 6 and is utilized in working on the intermediate pressure drum 8. The leakage from the chamber 15 into the chamber 23 60 is carried by the pipe 24 into the chamber 9, and in conjunction with the steam exhausted from the drum 8 it works on the low pressure drum 10.

65 Liquid packing means or other suitable

glands are mounted in the chambers 25 and 26 at either end of the elastic fluid turbine and form a hermetically tight joint between the exterior casing 3 and the rotating shaft 2 of the turbine.

Fig. 2 is a longitudinal section of an elastic fluid turbine fitted with a differently located pressure chamber 16 and a modified system of leakage passages. The motive fluid at initial pressure is admitted to the chamber 16 through the pipe 17. The leakage of the high pressure fluid from the chamber 5 through the packing collars 13 supplements the pipe 17 in maintaining the desired fluid pressure in the chamber 16. 70 The leakage from the chamber 16 into the chamber 15 is carried by the pipe 22 into either the chamber 7 or the chamber 9 by the use of a conveniently located three-way valve 27. The leakage from the chamber 15 into the chamber 23 is carried by the pipe 24 into the chamber 9. The secondary inlet port 12 can still be retained with this system of leakage pipes, as the low pressure fluid from the chamber 15 can be admitted to the chamber 9 by the use of the three-way valve 27 when the chamber 7 is under initial pressure. The chambers 25 and 26 contain liquid packing means for sealing the joint between shaft 2 and the exterior casing 3 of 95 the turbine.

Still another modification of this balancing-chamber may be used in connection with a vertical elastic fluid turbine. If we consider the shaft 2 of the turbine in Fig. 2 100 supplied with a step bearing at the exhaust end of the exterior casing 3 and a flexible coupling at the other end of the shaft for connecting an electric generator or some such machine the figure may be utilized as 105 an illustration of a vertical turbine. In such turbines the step bearing of the shaft 2 is designed to support the entire weight of the rotating element in addition to the downward pressure of the motive fluid on 110 the drums 8 and 10. The chamber 16 and its inclosed disk can be so proportioned that it will balance the fluid pressure and the weight of the rotor, and the pressure of the shaft on the step bearing will be materially 115 decreased. In fact such a degree of balancing may be obtained that the spindle will rotate exerting practically no pressure on the step bearing.

If the turbine is so constructed that the 120 fluid pressure on the drums 8 and 9 is in opposition to the pressure exerted by the weight of the rotor the balancing action of the chamber 16 is just as effective.

In marine turbines in which the propeller 125 thrust either increases or decreases the longitudinal thrust of the rotor, due to lateral fluid pressure, the balancing-chamber is effective, and the rotor can be so arranged and proportioned in connection with the 130

balancing-chamber that the propeller thrust can be balanced either while the turbine is running ahead or reversing.

The device above described is self-adjusting and will automatically fit itself to any change of load, vacuum or pressure, and by means of the auxiliary passages all of the motive fluid has an opportunity to work efficiently within the turbine.

10 Having thus described my invention, what I claim is:

1. In an elastic fluid turbine, means for exerting lateral pressure on the rotor of said turbine in opposition to any end thrust of

15 the said rotor, agents dependent on said end thrust for regulating the amount of lateral or balancing pressure exerted and means for utilizing the excess of balancing fluid pressure as a working agent in said turbine.

20 2. In an elastic fluid turbine, means for applying fluid pressure in opposition to the end thrust of the turbine shaft, means for automatically regulating such pressure, in accordance with the degree of end thrust 25 and means for utilizing the excess of pressure as a working agent in said turbine.

3. In an elastic fluid turbine, a pressure chamber, means within said chamber for exerting lateral pressure on the rotor of 30 said turbine, instrumentalities auxiliary to said chamber and actuated by said rotor for varying said balancing pressure and means for utilizing the excess of pressure as a driving agent in said turbine.

35 4. In an elastic fluid turbine, a rotatable shaft, a fluid pressure chamber surrounding the shaft, a source of fluid supply communicating with the said chamber, a member carried by the shaft and subjected to the fluid 40 pressure in the said chamber means whereby the fluid pressure in the chamber is varied in proportion to the end thrust imparted to the shaft and means for utilizing the excess of fluid in said chamber as a driving agent 45 for said turbine.

5. In an elastic fluid turbine, a rotatable shaft, a fluid pressure chamber encircling the shaft, a member carried by the shaft and subjected to the fluid pressure in the said 50 chamber, a source of fluid supply communicating with the chamber means whereby the fluid pressure in the said chamber is automatically varied as the end thrust imparted to the shaft varies and means for utilizing the excess of fluid pressure in said chamber as motive fluid in said turbine.

6. In an elastic fluid turbine, a rotatable shaft, a chamber surrounding said shaft, a source of fluid supply communicating with 60 said chamber, a member carried by said shaft and subjected on one side to the fluid pressure in said chamber and means whereby the amount of fluid supplied to said chamber is varied in accordance with the end 65 thrust imparted to said shaft.

7. In an elastic fluid turbine, a rotatable shaft, a pressure chamber surrounding said shaft, a source of fluid supply communicating with said chamber, a member carried by said shaft and subjected to fluid pressure 70 in said chamber, an interleaving seal between said member and the walls of said chamber and means, dependent on the end thrust encountered by said shaft for rendering said interleaving seal effective and for 75 regulating the fluid pressure in said chamber.

8. In an elastic fluid turbine, a rotatable shaft, a casing surrounding said shaft, a chamber within said casing, members mounted on said shaft so as to form walls for said chamber, a fluid supply to said chamber and means, dependent on the position of said members, for controlling the fluid pressure within said chamber. 80

9. In combination with an elastic fluid turbine, a fluid-actuated thrust relieving device, fluid admission means for said device automatically regulable in accordance with the longitudinal position of the turbine rotor 90 and means for passing the exhaust from said device to the turbine to be relieved. 85

10. In combination with an elastic fluid turbine, a fluid-actuated thrust relieving device, means for supplying said device with 95 working fluid, means for passing the exhaust from said device to the turbine to be relieved and means automatically regulable in accordance with the longitudinal position of the turbine rotor for controlling said 100 exhaust.

11. In combination, an elastic fluid turbine, a thrust relieving device located in a casing separated from the working passages of said turbine, means, dependent on the thrust encountered by the turbine, for controlling the delivery of motive fluid to said device and means for delivering the exhaust from said device to a working portion 105 of the turbine. 110

12. In combination, an elastic fluid turbine, a fluid-actuated relieving device, means for controlling the delivery of fluid to said device in accordance with the thrust encountered and means for delivering the exhaust fluid from said device to the turbine 115 to be relieved.

13. In combination with an elastic fluid turbine, through the stages of which the working fluid flows in one axial direction 120 only, a fluid-actuated thrust relieving device located adjacent the high pressure end of said turbine, means for delivering the exhaust from said device to the turbine to be relieved and means, dependent on the 125 amount of thrust, for varying the admission of fluid to said device.

14. In combination with an elastic fluid turbine, through the stages of which the working fluid flows in one axial direction 130

only, a fluid-actuated thrust relieving device located adjacent the high pressure end of said turbine, means for delivering the exhaust from said device to the turbine to be relieved and means, dependent on the amount of thrust, for supplying said device with working fluid.

15. In combination, an elastic fluid turbine, a thrust balancing device, means for delivering working fluid to said device and means, dependent on the thrust encountered by the turbine, for proportioning the delivery of exhaust from said device to a working portion of the turbine.

16. In combination, an elastic fluid turbine, a thrust relieving device, means for delivering working fluid to said device and means, dependent on the thrust encountered by the turbine, for proportioning the delivery of exhaust from said device to the turbine to be relieved.

17. In combination, an elastic fluid turbine, a thrust relieving device therefor, means, within the turbine casing, for delivering working fluid to said device and means, dependent on the thrust encountered by said turbine, for delivering the exhaust from said device to a working portion of the turbine.

18. In combination, an elastic fluid turbine, a thrust relieving device, means, located within a chamber separated from the working passages of the turbine, for delivering working fluid to said device and means, dependent on the thrust encountered by said turbine, for delivering the exhaust from said device to the turbine to be relieved.

19. In combination, an elastic fluid turbine having a motive fluid supply port, a thrust relief device, means in communication with the turbine casing but separated from the motive fluid supply port for delivering motive fluid to said device and means dependent upon a thrust encountered by the turbine for controlling the size of the exhaust opening from said device.

20. In combination, an elastic fluid turbine, a fluid-actuated thrust relieving device, means whereby the exhaust fluid from said device is delivered to the turbine to be relieved and means for controlling the amount of fluid so delivered in accordance with the amount of thrust encountered by said turbine.

21. In combination, an elastic fluid turbine, a fluid-actuated thrust relieving device, regulable means for delivering motive fluid to said device and means, dependent on the amount of thrust encountered, for passing the exhaust from said device to the turbine to be relieved.

22. In combination, an elastic fluid turbine, a thrust relieving device therefor, and means independent of the supply port for the turbine and, dependent on the thrust en-

countered by said turbine, for controlling the delivery of motive fluid to said device and the exhaust of motive fluid from said device said means being in communication with the turbine casing.

23. In combination, an elastic fluid turbine, a thrust relieving device therefor, independent regulable means separate from the thrust relieving device for controlling the delivery of motive fluid to said device in accordance with the thrust encountered by the turbine and means for controlling the exhaust from said device said thrust relieving device and turbine being in communication.

24. In combination, an elastic fluid turbine, a thrust relieving device therefor, means separate from the thrust relieving device dependent on the thrust encountered by said turbine, for controlling the delivery of motive fluid to said device and means for controlling the exhaust therefrom in accordance with the thrust encountered said thrust relieving device and turbine being in communication.

25. In combination, an elastic fluid turbine, a thrust relieving device therefor, means, dependent on the thrust encountered by said turbine, for controlling the delivery of motive fluid to said device, means for delivering the exhaust fluid from said device to the turbine and means for controlling the exhaust delivery of said device in accordance with the thrust encountered by the turbine.

26. In combination, an elastic fluid turbine, a thrust relieving device therefor, means, dependent on the thrust encountered by said turbine, for controlling the delivery of motive fluid to said device, means for delivering the exhaust fluid from said device to a working passage of said turbine and means, dependent on the amount of thrust encountered by the turbine, for controlling the exhaust delivery of said device.

27. In an elastic fluid turbine, a thrust relieving device comprising a chamber formed within the turbine casing and surrounding the turbine shaft, a member carried by the shaft and forming a wall of said chamber, means for permitting a flow of motive fluid through said chamber and means, dependent on the thrust encountered by the turbine, for varying the flow of motive fluid through said chamber to thereby control the pressure within said chamber.

28. In an elastic fluid turbine, a thrust relieving device comprising a chamber surrounding the turbine shaft, a member carried by said shaft and forming a wall of said chamber, a fluid supply for said chamber, an interleaving seal between said member and the stationary wall of said chamber and means for varying the effectiveness of said seal for the purpose of regulating the pressure within said chamber.

29. In an elastic fluid turbine, a thrust relieving device comprising a chamber surrounding the turbine shaft, a member carried by the shaft and forming a wall of said chamber, a fluid supply for said chamber, an interleaving seal between said member and the stationary wall of said chamber and means, dependent on the thrust encountered by said turbine, for varying the ef-

fectiveness of said seal for the purpose of 10 regulating the pressure within said chamber.

In testimony whereof, I have hereunto subscribed my name this 27th day of February, 1905.

RAYMOND N. EHRHART.
